CLAIM

The ornamental design for a wipe package as shown and described.

DESCRIPTION

FIG. 1 is an isometric view of a wipe package in an open configuration showing our new design;

FIG. 2 is a rear elevation view thereof;

FIG. 3 is a front elevation view thereof;

FIG. 4 is a left side elevation view thereof, the right side elevation view being a mirror image thereof;

FIG. 5 is a top plan view thereof;

FIG. 6 is a bottom plan view thereof;

FIG. 7 is an isometric view of a wipe package in a closed configuration showing our new design;

FIG. 8 is a rear elevation view thereof;

FIG. 9 is a front elevation view thereof;

FIG. 10 is a left side elevation view thereof, the right side elevation view being a mirror image thereof;

FIG. 11 is a top plan view thereof; and,

FIG. 12 is a bottom plan view thereof.

The dash-dash broken lines in the drawings depict portions of the wipe package that form no part of the claimed design. The dash-dot lines in the drawings define the boundaries of the claimed design and form no part of the claimed design.

1 Claim, 11 Drawing Sheets
